SIMON M. LUTZ, OF BEDFORD, PENNSYLVANIA.

DESIGN FOR A GAME-BOARD.

SPECIFICATION forming part of Design No. 29,999, dated January 10, 1899.

Application filed November 17, 1898. Serial No. 696,727. Term of patent 7 years.

To all whom it may concern:

Be it known that I, SIMON M. LUTZ, of Bedford, in the county of Bedford and State of Pennsylvania, have invented and produced 5 a new and original Design for a Game-Board, of which the following is a full, clear, and exact description.

In the drawings, Figure 1 shows a plan view of a game-board embodying my design, and 10 Fig. 2 shows a cross-section of the same.

My design consists in the rectangular field traversed at regular intervals by parallel lines A, intersected at right angles by a similar series of parallel lines A', there appearing on 15 the middle line of each series a band B, which appears half on one side and half on the other side of such middle line.

The leading feature of my design consists in the rectangular field traversed by two series of regular parallel lines intersecting at 20 right angles and a band appearing on the middle line of each series and lying one-half on one side and one-half on the other side of such middle line.

I claim—

25 The design for a game-board herein shown and described.

SIMON M. LUTZ.
